TELEVISION TRANSMITTER

Arthur W. Vance, Haddonfield, N. J., assignor to
 Radio Corporation of America, a corporation of
 Delaware

Application March 30, 1937, Serial No. 133,773

6 Claims. (Cl. 178—7.2)

My invention relates to television transmitters, and particularly to transmitters of the type employing a cathode ray tube for converting light images into picture signals for transmission to a receiver.

A preferred form of cathode ray transmitter tube is the type having a mosaic of photo-sensitive globules upon which a light image is projected whereby an electric charge is stored upon each globule. These charges are released as picture signals by scanning the mosaic with an electron beam.

An objectionable characteristic of this transmitter tube is that spurious signals are mixed with the picture signals as they appear in the output circuit of the tube, due to what is referred to as the "black spot" effect. Unless compensation or correction of some kind is provided, the spurious signals result in uneven shading of the received picture. The "black spot" effect may be greatly reduced by mixing shading signals with the picture signals, as described and claimed in Patent No. 2,166,712, issued July 18 1939, in the name of A. V. Bedford, and assigned to the Radio Corporation of America. However, the Bedford method of reducing the uneven shading is not entirely satisfactory, partly because it requires a trained operator for manually adjusting the shading controls.

It is accordingly an object of my invention to provide an improved means for and method of reducing or eliminating the so-called "black spot" effect or similar phenomenon.

A further object of my invention is to provide an improved means for and method of transmitting pictures from motion picture film.

A still further object of my invention is to provide an improved amplifier for reversing the polarity of electrical signals.

In a preferred embodiment of my invention, I print a moving picture film with certain of the picture frames positive and the others negative. Preferably, alternate picture frames are positive and the other picture frames negative. Images of these picture frames are projected upon the cathode ray tube mosaic in the usual way. In order to transmit all picture frames to the receiver with the same polarity, means are provided for reversing the polarity of a picture signal amplifier each time the picture frames change from positive to negative and vice versa.

The action of this system in eliminating the "black spot" is as follows:

Since the major part of the "black spot" or uneven shading is determined by the characteris-

tics of the mosaic itself, the signal representing the "black spot" will remain substantially unchanged for successive picture frames. In the preferred system, the "black spot" signal will be reversed at the transmitter for each new picture frame whereby the "black spot" signal at the receiver and the corresponding uneven shading on the fluorescent screen of the cathode ray receiver tube is similarly reversed. Thus positive and negative "black spots" appear alternately at the receiver, and since they alternate at a rate above persistence of vision, they are "balanced out" in the eye of the observer.

The invention will be better understood from the following description, taken in connection with the accompanying drawings, in which

Figure 1 is a schematic and block diagram of a television transmitter embodying my invention.

Figure 2 is a circuit diagram of the reversing amplifier employed in the system shown in Fig. 1.

Figure 3 is a view of the shutter disc shown in Fig. 1, and

Figures 4 and 5 are views of moving picture film showing how it may be printed for transmission in accordance with my invention.

Referring to Fig. 1, a television transmitter system is illustrated which includes a cathode ray transmitter tube 1 of the type described in an article by Dr. V. K. Zworykin which appears in the January, 1934, issue of The Journal of The Franklin Institute. This tube comprises an evacuated envelope having an electron gun 2, a focusing and accelerating anode 3, and a mosaic 4 of light sensitive elements thereon. Deflecting means, such as deflecting coils 6 and 7, are provided for deflecting the electron beam horizontally and vertically, respectively, in order to scan the mosaic 4 with the electron beam.

To produce the desired current flow through the deflecting coils 6 and 7 for deflecting the electron beam, an electric discharge tube impulse generator is provided. This generator comprises a main oscillator 8, from which are derived electrical impulses of the desired frequency for horizontal deflection and also electrical impulses of the desired frequency for vertical deflection. The main oscillator 8 may be a blocking oscillator of the type described in U. S. Patent 1,999,378, a multi-vibrator, or the like.

The voltage impulses produced by the oscillator 8 are impressed upon a chain of frequency dividers 9, 11 and 12, each of which may be a blocking oscillator operating the same as the main oscillator 8 but at a lower frequency. Each oscil-

lator is locked in step with the oscillator of next highest frequency.

The frequency of the main oscillator output is divided by seven in each of three frequency dividers, as indicated on the drawings, to produce voltage impulses occurring at the rate of 60 per second, this being the desired vertical deflecting or frame frequency. The 60-cycle impulses are supplied to the input circuit of a saw-tooth wave generator or deflecting circuit 13, which converts them into voltage impulses of the necessary shape for causing a flow of current having a saw-tooth wave shape, through the deflecting coils 7.

The horizontal deflecting impulses are obtained by impressing a portion of the output energy of the main oscillator 8 upon the input circuit of a frequency divider 14 which divides the frequency of the main oscillator output by two to produce 10,290 impulses per second. The output of the frequency divider 14 is impressed upon a saw-tooth wave generator or deflecting circuit 16 which has its output connected across the horizontal deflecting coils 6 for causing a flow of saw-tooth current therethrough.

It will be noted that the vertical deflecting and horizontal deflecting frequencies are such as to produce a 343 line picture, the scanning being interlaced. Although my invention is described in connection with an interlaced scanning system, it should be understood that it is of general application, and that its usefulness is not restricted to this system.

Motion picture film having thereon the pictures to be transmitted is indicated generally at 17. The picture frames are moved intermittently into position in a film gate 18 by means of an intermittent mechanism 19 of conventional construction. The intermittent mechanism is driven by means of a synchronous motor 21 at the proper speed to project 60 picture frames per second upon the mosaic 4. A shutter disc 22 is also driven by the synchronous motor, this disc being rotated at 60 rotations per second. As shown in Fig. 3, the shutter disc has a single opening 23 therein, whereby the shutter periodically cuts off the light projected toward the mosaic. The timing of the shutter disc 22 is so related to that of the intermittent mechanism and to that of the deflecting means that a picture frame is projected upon the mosaic 4 and then scanned by the cathode ray after the shutter disc has cut off the projected light and during the time the film is being moved into position for projection of the next picture frame. This method of transmitting pictures from motion picture film is described and claimed in Patent No. 2,166,214, issued July 18, 1939, in the name of R. D. Kell, and assigned to the Radio Corporation of America.

In order to keep the scanning of the mosaic in the correct time relation to the projection of pictures thereon, a suitable control circuit, indicated at 24, is provided for maintaining the oscillator locked in with the 60-cycle power line to which the motor is connected. One satisfactory type of control circuit for this purpose is described and claimed in Patent No. 2,137,010, issued November 15, 1938, in the name of A. V. Bedford, and assigned to the Radio Corporation of America.

Current from the 60-cycle line is impressed upon the input circuit of the control circuit through a transformer 26 in such phase that it adds 60-cycle impulses which are supplied to the

control circuit from frequency divider 12 through a wave shaping amplifier 27.

It will be apparent from the foregoing description that the control circuit 24 and its associated circuits cause the mosaic 4 to be scanned synchronously with the projection of the picture frames thereon. The exact picture projection and scanning operation is not described in detail as it is, in itself, no part of the present invention.

The picture signals appear across a resistor 28 connected between the mosaic 4 and the second anode 3, and are impressed upon a picture signal amplifier 29 which amplifies them and feeds them through a reversing amplifier 31 to a radio transmitter 32.

In order to maintain the scanning at the receiver synchronized with the scanning at the transmitter, the horizontal synchronizing impulses are impressed through a wave shaping amplifier 33 upon a suitable amplifier stage in 20 the transmitter 32. Likewise, the vertical deflecting impulses are impressed through a wave shaping amplifier 34 upon a suitable amplifier stage transmitter 32. Preferably, the horizontal and vertical synchronizing impulses are impressed 25 upon such an amplifier stage in the transmitter 32 so that they appear at the receiver with a polarity opposite to the polarity of the picture signals in the white direction, whereby the synchronizing signals and picture signals may be 30 more easily separated. It will be understood that, in accordance with usual practice, the horizontal synchronizing impulses are transmitted at the end of each scanning line while the vertical synchronizing impulses are transmitted at the end 35 of each picture frame whereby the picture signals and the synchronizing signals are not transmitted simultaneously.

As previously described, and as shown in Figs. 4 and 5, in the preferred embodiment of my 40 invention the motion picture film is printed with alternate picture frames positive and the remaining picture frames negative. It will be apparent that during the transmission of a film of this character, the picture signals appearing across 45 the output resistor 28 of the transmitter tube, which represent a complete picture frame, will alternately be positive and negative in polarity with respect to each other, corresponding to the reversal of the picture frames. In order to 50 prevent a corresponding reversal of the picture frames at the television receiver, the reversing amplifier 31 is included in the output channel of the transmitter tube.

As will be described in detail later, the polarity 55 of the reversing amplifier is reversed by supplying to it a rectangular voltage wave having a fundamental frequency of 30 cycles per second, as indicated at 36. Since it is essential that this reversing voltage wave occur in the correct time 60 relation to the scanning of the mosaic, it is derived from the same 60-cycle frequency divider 12 which supplies the vertical deflecting circuit.

The 60-cycle impulses from the frequency divider unit 12 are supplied through a conductor 65 37 to another frequency dividing unit indicated at 38, such as a blocking oscillator, adjusted to lock in at 30 impulses per second. These 30-cycle impulses are supplied to an amplifier 39 tuned to 30 cycles per second for producing a 70 30-cycle sine wave. This sine wave is then converted into the rectangular impulses indicated at 36, by passing it through suitable clipping tubes, indicated at 41, as is well known in the art. The rectangular impulses are supplied 75

through a transformer 42 to the reversing amplifier 31, the primary and secondary of the transformer being loaded by resistors to avoid the production of transients in the transformer.

5 A suitable reversing amplifier is shown in detail in Fig. 2. This amplifier comprises two amplifier channels connected in parallel, one of these channels including the amplifier tubes 46 and 47, and the other channel including the amplifier tube 48. The tube 46, which is provided for the purpose of making the outputs of the two channels of opposite polarity, preferably is of the screen grid type having a cathode 49, a control grid 51, a screen grid 52, and a plate 53. 10 The tube 47, which is blocked periodically to render the channel ineffective to pass signals, also preferably is of the screen grid type having a cathode 54, a control grid 56, a screen grid 57, and a plate 58. 15 The plate and grid circuits of the tubes 46 and 47, respectively, are resistance coupled through a plate resistor 59, a coupling condenser 61, and a grid resistor 62. The resistor 59 is provided with a short-circuiting connection 63 and a 20 variable tap 64, whereby the gain of the amplifier tube 46 may be adjusted to unity. 25

The output circuit of amplifier tube 47 includes a plate resistor 66 through which voltage is supplied to the plate 58 from a battery 67 30 or other voltage source. This battery 67 also supplies voltage to the plate 53 of tube 46 through a conductor 68 and the plate resistor 59.

The second channel includes only the one amplifier tube 48 in the specific circuit shown, 35 this tube preferably being of the screen grid type having a cathode 69, a control grid 71, a screen grid 72, and a plate 73.

The input circuits of tubes 46 and 48 are connected in parallel, the control grids 51 and 71 being connected to each other through a conductor 74 and each control being suitably biased 40 by voltage supplied through a grid resistor 76 by a biasing source 77.

The output circuits of tubes 47 and 48 are also 45 connected in parallel, the plate 73 of tube 48 being connected to the plate 58 of tube 47 through a conductor 78, whereby picture signals which are impressed upon the input circuits of tubes 46 and 48 appear across the resistor 66 50 either as the output of the tube 47 or the tube 48, depending upon which one of the tubes is unblocked at the moment.

The tubes 47 and 48 are blocked alternately by applying the rectangular voltage previously 55 mentioned to their screen grids 57 and 72. This is accomplished by connecting one end of the secondary of transformer 42 to the screen grid 57, and by connecting the other end of the secondary to the screen grid 72 while the mid- 60 point of the secondary is effectively connected to A. C. ground through the conductors 79 and 81 and the battery 67. The screen grids of the tubes 46, 47 and 48 are maintained as a positive direct current potential by the lower sec- 65 tion of the battery 67.

The rectangular voltage wave 36 which is supplied to the transformer 42 is of sufficient amplitude to block the tubes 47 and 48 alternately. Thus, one amplifier channel is inoperative 70 during the period the other channel is operative and, since the amplifier channels have outputs of opposite polarity, the picture signals supplied to the amplifier input are reversed in polarity each time a tube is blocked.

75 One important feature of my reversing am-

plifier is that the rectangular voltage impulses which are supplied through the transformer 42 do not produce a disturbance across the output resistor 66 of the amplifier, since they do not change the current flow therethrough. The reason for this is that when the screen grid of tube 47 goes negative to block the tube 47, the screen grid of the tube 48 goes positive, whereby the plate current of one tube is increased the same amount the plate current of the other tube is decreased. It will be apparent that tubes 47 and 48 should be operated along the straight portion of their characteristic by the varying screen grid voltage, if a perfect balancing out of the reversing impulses is to be obtained. 15 Also, the tubes should have similar characteristics and the tube 46 should be adjusted for unity gain.

A moving picture film may be prepared for transmission in accordance with my improved 20 method by printing a single film, as shown in Figs. 4 and 5, for example, from two separate films, one positive and one negative. The printing may be done by any suitable optical method.

It should be understood that it is within the 25 scope of my invention to project positive and negative pictures alternately upon the cathode ray tube mosaic from two separate films, one positive and the other negative, instead of from a single specially printed film.

In the system shown in Fig. 1, the film is run 30 through the projector at the rate of 60 frames per second. Obviously, if conventional practice is followed, the pictures will be taken by a camera which takes pictures at this same speed, 60 35 frames per second. In this case, the film will be printed as shown in Fig. 4. In order to permit the use of standard film having picture frames taken at the standard rate of 24 per second, the standard film may be printed as 40 shown in Fig. 5, alternate frames from the standard film being printed twice and the other frames being printed three times. Such a film, run at 60 individual frames (several of them identical) 45 per second, is running at the rate of 24 original picture frames per second.

Although I have described a system in which the mosaic is scanned at the power line frequency, it will be understood that the film may be projected upon the mosaic at the rate of 24 50 frames per second, and the mosaic scanned at a corresponding rate, say 48 times per second, with interlaced scanning. In this case, the film preferably is printed as shown in Fig. 4.

55 I claim as my invention:

1. The method of transmitting pictures from motion picture film which comprises the steps of printing alternate picture frames positive and the other picture frames negative, converting said picture frames successively into picture signals and reversing the polarity of said picture signals each time the picture frame which is being converted into picture signals changes from positive to negative or vice versa. 60

2. The method of transmitting pictures from motion picture film which comprises the steps of printing certain picture frames positive and printing other picture frames interspersed with said positive frames negative, converting suc- 70 cessive positive and negative picture frames into picture signals, and reversing the polarity of said picture signals each time the picture frame from which said picture signals are being derived is changed from positive to negative or vice versa. 75

3. In a television system having a cathode ray tube with a photo-sensitive screen, the method of transmitting pictures from motion picture film which comprises the steps of printing alternate picture frames positive and the remaining picture frames negative on a single film, projecting said picture frames successively upon said screen to produce an electron image whereby picture signals are produced as said electron image is scanned by a cathode ray, and reversing the polarity of said picture signals each time the picture projected upon said screen is changed from positive to negative or vice versa.

4. In a television system having a cathode ray tube with a photo-sensitive screen, the method of transmitting pictures from motion picture film which comprises printing positive and negative picture frames in interspersed relation on a single film, projecting said frames upon said screen to produce an electron image, scanning said image with the cathode ray to convert said pictures into picture signals, and amplifying and reversing the polarity of said picture signals each time the projected picture frame on said screen changes from positive to negative or vice versa whereby the polarity of spurious signals but not of picture signals is reversed.

5. In a picture transmitter, a cathode ray transmitter tube of the type having a mosaic of capacity elements, means for projecting alternately upon said mosaic positive and negative picture images, means for scanning said mosaic with the cathode ray for converting said picture images into picture signals, an amplifier connected to amplify said picture signals, and means for reversing the polarity of said amplifier each time the picture image projected upon said mosaic changes from positive to negative or vice versa.

6. In a picture transmitter, a cathode ray transmitter tube of the type having a mosaic of capacity elements, means for projecting alternately upon said mosaic positive and negative picture images at a rate greater than persistence of vision, means for scanning said mosaic with said cathode ray in synchronism with the projection of said picture images whereby picture signals are produced, an amplifier connected to amplify said picture signals, and means for reversing the polarity of said amplifier in synchronism and in phase with said scanning.

25

ARTHUR W. VANCE.
